UNITED STATES PATENT OFFICE.

JOHN L. LEWIS, OF PITTSBURG, PENNSYLVANIA.

IMPROVEMENT IN ROLLING ANGLE-IRON.

Specification forming part of Letters Patent No. 42,495, dated April 28, 1864.

To all whom it may concern:

Be it known that I, JOHN L. LEWIS, of Pittsburgh, in the county of Allegheny and State of Pennsylvania, have invented a new and useful Improvement in Rolling Angle-Iron; and I do hereby declare that the following is a full, clear, and exact description of the same, reference being had to the accompanying drawings, forming a part of this specification, in which—

Figure 1 represents a front elevation of the rollers which I use in rolling angle-iron. Fig. 2 is a transverse vertical section of the same. Figs. 3, 4, and 5 are diagrams illustrating the difference between the usual and between my improved mode of rolling angle-iron.

Similar letters of reference in the several views indicate corresponding parts.

This invention consists in the employment or use, in rolling angle-iron, of rollers with flat faces and a central triangular ridge or groove in such a manner that the bar from which the angle iron is to be rolled can be introduced between the rollers flat instead of cornerwise, and both sides of the angle-iron when finished run parallel to the layers of the original bar and not crosswise, as is inevitably the case with one side of angle-iron rolled in the ordinary manner; also, in the arrangement of flanges projecting at right angles above or beyond the face of one of each pair of rollers in such a manner that the edges of the iron during the process of rolling are protected, and angle-iron with sharp, square edges can be produced.

To enable others skilled in the art to make and use my invention, I will proceed to describe it.

A A' B B' C C' D D' represent a series of rollers which have their bearings in a common frame, E, the rollers A B C D being on one and the rollers A' B' C' D' on another shaft. The roller A is made with a flat face, a, provided with a triangular central ridge, a*, and the corresponding roller, A', is also made with a flat face, a', corresponding in width to the face of the roller A and with a triangular central groove, a** just opposite the ridge a* and of corresponding width and depth. The second pair of rollers, B B', is the reverse from the first pair, the upper roller, B, being pro-

vided with a groove, b*, and the lower roller, B', with a ridge, b**, between the flat faces b and b', respectively. The third pair of rollers, C C', are similar to the first pair, the upper roller, C, being made with a flat face, c, and ridge c*, and the lower roller, C', with a flat face, c', and groove c**.

The finishing-rollers D D' are similar to the ordinary rollers for rolling angle-iron without a flat face, the upper roller, D, forming a rectangular ridge corresponding to the groove D', that occupies the entire face of the lower roller.

The rollers A' B' C' are provided with flanges d, which project above the flat faces a' b' c' and beyond the edges of the corresponding rollers, A B C. These flanges are at right angles to the flat faces of the rollers, and they protect the edges of the iron and prevent said edges from getting round. The advantages of my rollers and their superiority over ordinary rollers will be best understood by referring to the diagrams represented in Figs. 3, 4, and 5.

The bars E, from which angle-iron is rolled, are composed of a series of layers, e, as indicated by dotted lines in Figs. 4 and 5, and they are generally square, or nearly so.

In rolling angle-iron with the ordinary rollers, said bars are introduced cornerwise, as clearly shown in Fig. 3. In fact, it is impossible to introduce them in any other way, because they do not lay flat on any part of the lower roller. The angle-iron F produced by such rollers, therefore, will be in such relation to the original bar that the wing f is parallel and the wing f' at right angles to the original layers of said bar, (shown in Fig. 4,) and from its relation to said layers the wing f' is liable to break, and a poor article is the result.

With my rollers the original bar can be introduced flat, because it lays flat on the face of the first roller, A', and when the bar leaves the rollers C C' it has assumed the shape shown in Fig. 5. The rollers D D' simply turn up the two wings. The relation of the angle-iron F' to the bar E, therefore, will be such that both its wings are parallel to the original layers of the bar, and a strong and durable article is produced.

What I claim as new, and desire to secure by Letters Patent, is—

So constructing rolls for rolling angle-iron

as that the "pile" constituting the fagot shall be caught between the rolls flat instead of cornerwise, and so rolling it as that one-half of both sides or wings shall remain parallel with the face or top of the pile until very nearly reduced to its proper thickness, when by passing it through a plain rectangular groove

in said rolls, the wings or sides shall be turned up and finished with the grain conformable to the layers of the original bar.

JOHN L. LEWIS.
